HAIR CLAMP

Application filed October 30, 1931. Serial No. 572,008.

This invention relates to improvements in the art of hair waving and refers more particularly to a device for clamping a strand of hair preparatory to the waving treatment.

5 Hair clamps are known comprising bars connected with each other by means of a pivoted link. It has been found that such clamps are quite inconvenient in use as a considerable amount of time is spent in opening and closing them during their application to a strand and removal therefrom. Both hands of an operator are needed to open the hair clamp and this operation takes quite a long time. Furthermore, the hair clamp 10 becomes quite hot during the hair waving process and the hands of the operators are liable to be injured by its heated metal parts while opening and removing the clamp.

An object of this invention is to eliminate 20 the above mentioned drawbacks by providing a hair clamp which can be easily and quickly opened by the use of one hand only, thus leaving the other hand of the operator free.

Another object is to provide a hair clamp 25 having a lock requiring the smallest possible surface of contact between the hand and the clamp while opening said lock, said surface being situated furthest from the heated parts of the clamp for the purpose of eliminating 30 the danger of burning the hands of the operator.

A further object is to provide a hair clamp having a lock which cannot spring open accidentally while the hair is being treated.

35 Still another object is to provide a hair clamp having a lock by means of which the two bars of the clamp can be brought into very close relationship with each other, thus 40 enabling the strand of hair to be held tightly during the hair waving process.

The invention will appear more clearly from the following detailed description, when taken in connection with the accompanying 45 drawing, which illustrates preferred embodiments of the inventive idea.

In the drawing—

Figure 1 is a perspective view of a hair clamp, showing the same in opened position; 50 Figure 2 is a plan view of the hair clamp

in closed position, with parts broken away and shown in section;

Figure 3 is an end view of the hair clamp; Figure 4 is a transverse section on the line 4—4 of Figure 2; and

55 Figures 5 and 6 show modified forms of the spring connecting the two clamp bars.

The hair clamp comprises two bars 7 and 8 connected with each other by means of a resilient spring 9, the two ends of the spring 60 9 being soldered or otherwise secured to adjacent ends of said bars. The bars 7 and 8 have the shape of narrow, flat strips and are interposed between heat-insulating straps 10, 11 and 12, 13, preferably made of cork. 65 The bar 7 is surrounded by a heat-insulating jacket 14, whereas the bar 8 is surrounded by a similar jacket 15. Both jackets are preferably made of rubber and are provided with grooves 16 which promote the circulation of 70 air during the waving process, the scalp being effectively protected from the heat issuing from the hair waving machine by the air circulating in these grooves.

75 The bar 8 is provided with a pivot 17 carrying a substantially U-shaped lever 18 adapted to receive the ends of the bars 7 and 8 and to lock the clamp by sliding over the cam edge of the bar 7 into a notch 19 of said bar. Due to this arrangement, the lever 18 80 cannot spring back while the hair clamp is closed, the two insulating jackets 14 and 15 being pressed tightly against each other in this closed position. The lever 18 is provided with an extension 20 used as a finger piece 85 to open and close the hair clamp.

In operation, a strand of hair adjacent the roots is passed between the two jackets 14 and 15 of the open hair clamp, which then 90 can be locked by pressing its two ends against each other and by swinging the lever 18 over the cam edge of the bar 7 until it reaches the notch 19. This operation can be easily performed with one hand. The surfaces of the jackets 14 and 15 provided with grooves 16 95 should be closest to the head so as to provide a circulation of air between the head and the clamp.

100 To open the hair clamp it is only necessary

to press a finger against the extension 20, thus swinging the lever 18 to the position shown in dotted lines in Figure 2. Due to the action of the spring 9, the clamp will then open 5 automatically and will release the strand of hair situated between the jackets 14 and 15.

In the modification shown in Figure 5, the bars 7 and 8 are interconnected by means of a bowed spring 21 having but a single coil, 10 whereas the spring 9 shown in Figure 2 consists of two coils.

According to the modification shown in Figure 6, the two ends of a bowed spring 22 15 are not rigidly connected with the bars 7 and 8, but are situated in suitable recesses 23 formed in the ends of these bars.

What is claimed is:

A hair clamp for use in permanent waving processes, comprising cooperating clamping bars having straight opposed faces between which a strand of hair is adapted to be held, there being an unobstructed space between the ends of said bars whereby said strands may be evenly distributed along the 25 same and securely held by said faces, a spring at one end of said clamp forming a connection between adjacent ends of said bars and operating to spread the latter apart, said spring also providing a yielding connection 30 between the ends which it connects so as to permit of a slight spreading movement of the latter relative to the opposite ends of the bars when a strand of hair is clamped therebetween, and a latching device at the latter ends 35 of said bars pivoted to one of them and engageable with the other for holding the same together against the spreading action of said spring.

In testimony whereof, I have affixed my 40 signature.

KARL GEORG STRÖHER.
